NATURAL CHEESE PACKAGE

Elmer E. Eldredge, Plymouth, Wis., assignor to
The Borden Company, New York, N. Y., a corporation of New Jersey

Application June 27, 1950, Serial No. 170,668

2 Claims. (Cl. 99—178)

1

A desideratum in the packaging of cheese, especially unprocessed cheese or cheese in its natural state, is to prevent molding and the formation of rind. This necessitates the effective exclusion of air from the wrapped cheese and natural cheese presents an especial problem in this regard since gases formed in the aging process must be allowed to escape.

The mere wrapping of the cheese in films which are impervious to air at atmospheric pressures is not a complete solution and the purpose of this invention is to provide a wrapper which effectively seals the cheese from the outside air.

This invention is based upon the observation that in spite of the impervious character of a wrapper, air enters the package through the folds of the wrapper. Where the film edges overlap smoothly and are in contact air does not get in, but it has been found that ingress of the air occurs where there are folds in the film, at the open ends of the wrapper, for example, where the film is folded down against the cheese to close the ends and complete the package.

This is due to the fact that when the material is folded back on itself, the reverse bend is usually not sharp enough to avoid the existence of a slight internal space along the line of fold which constitutes an air pocket or passage which is substantial under the circumstances and allows air to leak into the package and affect the cheese.

In accordance with this invention, that condition is counteracted by introducing a suitable oil between the layers of the folds. It is found that due to the minuteness of the spaces involved, the oil will by capillarity come to occupy the crevices and creases resulting from the folds and seal the potential passages for the air which have heretofore existed in such wrappings.

To secure this effect the film or foil must be oil-proof, that is, the oil must not enter substantially into the fiber of or permeate the film but must remain upon the surface, and the oil must be free flowing throughout the ranges of temperature at which cheeses are wrapped and stored.

The invention will be better understood from a more detailed description in connection with the accompanying drawings in which

Figs. 1, 2 and 3 are perspective views of a sheet in successive stages of folding to illustrate the principle of the invention, Fig. 1 being a perspective of the sheet open and having oil applied on the lower portion of its upper surface, Fig. 2 being a perspective of the same sheet folded over once along its central longitudinal axis, and

2

Fig. 3 being a perspective partially in section on larger scale of the same sheet folded again on the central vertical axis.

Fig. 4 is a perspective of a block of cheese in position on a sheet of wrapping material with oil preliminarily applied on the longitudinal marginal portions of the upper surface.

Figs. 5, 6, 7 and 8 are perspective views showing the cheese and wrapper of Fig. 4 in successive stages of wrapping, Figs. 6, 7 and 8 being on a scale somewhat larger than Figs. 4 and 5.

There are various suitable foils or films for the wrapping among which is vinylidene chloride polymer, a thermoplastic material of the vinyl group sold under the trade name of "Saran." It is a transparent, light weight, moisture proof film which is substantially impervious to gases at atmospheric pressures and which is non-absorptive of oils. Various oils are suitable for the purpose, among them mineral oils such as paraffin oil.

The principle upon which the invention depends is illustrated in Figs. 1, 2 and 3. A sheet 10 of oil-proof material such as "Saran" above identified, has a film of oil 11 applied thereon, for instance merely along its lower edge. It is then folded double along its middle longitudinal line, the two faces being brought together with the oil between them, as shown in Fig. 2. This fold leaves an air pocket or passage 12 along the line of fold, the thickness of the material and the size of the pocket 12 being exaggerated in the drawing for the sake of illustration. The oil however travels up by capillary attraction and occupies the entire space between the two layers of the fold including the pocket or passage 12.

This oil in the passage 12 acts as a trap or seal against the transmission of air therethrough. Any defect in or insufficiency of the seal is remedied by putting a transverse fold in the crease which forms the passage. This is done by folding the sheet a second time along a line across the first line of fold. This is illustrated in Fig. 3, the second fold there being at right angles to the first fold.

As shown in the view where the corner is broken away, the oil 11 has crept up and filled the entire space between the contacting faces including the passage 12, and the second fold puts a kink in the passage 12 and so effects a complete seal against gases at atmospheric pressures.

The remaining figures illustrate the application of this principle to the wrapping of cheese. Fig. 5 A sheet 10 of suitable oil-proof material, such

as "Saran," has a freely flowing oil, such as mineral oil, applied in a film 11 on one face along the two longitudinal edges, which are the edges on the ends to be folded. A block of cheese 15 is properly disposed on the oil-bearing face of the wrapper, as shown in Fig. 4, and the sheet is wrapped onto the cheese, as shown in Figs. 5 to 8, inclusive. The folding operation proceeds in the usual manner, the ends of the sheet first being brought up and overlapped on top of the block of cheese and the open ends of the wrapper then being folded against the end faces of the cheese. If desired the end folds may be secured down, as by pressure sensitive adhesive tape. In order better to illustrate the invention the order of the wrapping steps is shown in the drawings somewhat different from that above recited, and will be described as illustrated.

First, as shown in Fig. 5, the far end of the sheet is brought up on the top of the cheese, the proportions of the sheet being such that the far edge 16 is disposed on the near side of the middle line of the top face of the cheese. This brings the oil films 11 on the inner face of the rear vertical section 17 and the top horizontal section 18 of the partially wrapped sheet. Then, as shown, the portion 19 of the horizontal section that extends beyond the right end face of the cheese block as viewed in Fig. 5 is folded down against that end face. This causes the extending portion of the rear vertical section 17 to fold inwardly on itself along the oblique line 20, forming a right triangular inner layer 21 and an outer layer 22 which also includes a right triangular portion opposing the layer 21. The inner layer 21 joins the turned down portion 19 of the horizontal section at a vertical line of fold 23. As is seen, the oil 11 is on the inner faces of the portion 19 and of the inner layer 21 and on the inner face of the outer layer 22, as shown in the broken-away portion of the layer 21, and the oil overlaps for a portion of the area inside the triangular fold. The oil on the inner face of the portion 19 contacts the cheese and has no sealing function. However it is not deleterious and does no harm.

Next the near end of the sheet is brought up over the top of the block of cheese overlapping the first end and concealing the edge 16, the edge 24 of the overlapping end being disposed between the middle line and back edge of the top face of the cheese. This forms a near side vertical section 25 and an overlapping horizontal section 26 of the wrapper.

The extending portion 21 of the horizontal overlapping section 26 is turned down against the end face of the cheese. This causes the extending portion of the front vertical section 25 to fold inwardly on itself along the oblique line 28, forming a triangular inner layer (not shown) corresponding to the layer 21, and an outer layer 29 corresponding to the layer 22. The inner layer joins the turned down portion 27 at a vertical line of fold 30. The oil is on the contacting inner faces of the triangular fold, as indicated in the broken-away portion of the outer layer 29, and is also on the inner face of the turned down portion 27 which is partially in contact with the cheese and partially overlaps the portion 19.

Next the extending bottom horizontal section 31 of the wrapper is turned up against the end face of the cheese. This causes the outer layer 22 to fold inwardly upon itself along the oblique line 32 and similarly causes the outer layer 29

to fold inwardly upon itself along the oblique line 33. The fold along the line 32 forms an inner layer 34 which overlies the inner layer 21, and likewise the fold along the line 33 forms an inner layer 34a which overlies the inner layer formed by turning down section 27.

The oil 11 is on the inside upper edge of the section 31 where it overlaps the portions 19 and 27, and is on the inner faces of the turned up inner layers 34 and 34a of the triangular folds.

The lines of fold 20 and 32 meet at a point as do the lines of fold 28 and 33. Thus there are formed two triangular flaps designated generally by the numerals 35 and 36. To complete the wrapping on that end the flaps are turned down against the end of the package about the lines 23 and 30, respectively, as shown in Fig. 8 and, as above stated, may be secured down by adhesive tape if desired.

20 The opposite end of the package is closed in the same way, being shown unfolded in Fig. 7 and folded in Fig. 8.

25 The presence of the oil is indicated by stippling. It is the oil which is within the folded flaps 35 and 36 which is effective in sealing the air pockets or passages in the creases. The oil disposed on the inner faces of the overlaps 19, 27 and 31 is without essential sealing function and, except for the difficulty of selective application of the oil, could be eliminated.

30 It has been found that the internal creases formed by the folds along the lines 20, 32, 28 and 33 form air pockets or passages similar to the passages 12 and that when unimpeded, air enters 35 through those passages and forms a conveyance for mold spores and causes molding and surface oxidation and formation of rind on the cheese.

35 Due to the close contact of the faces of the component layers of the flaps 35 and 36, the oil 40 within the folds spreads by capillary attraction and comes to occupy the entire inner areas of the flaps and to fill the air pockets along the creases 20 and 28. Finally the folding over of 45 these creases along the lines 32 and 33 puts a kink in the creases at the apices x as was done with the passage 12 in the second fold of Fig. 3.

50 The conditions described with respect to the right end of the package as shown in the drawings are of course reproduced on the opposite end. It will be understood that the gases which 55 form within the wrapping from the aging process of the cheese develop sufficient pressure to effect their escape. To some extent these gases pass through the wrapper itself, depending upon 60 the degree of internal pressure, although such films as "Saran" are virtually impervious to air at atmospheric pressures. Moreover the fact that there is a superior internal pressure in the package assures the imperviousness of the wrapping to air. This also applies to the potential vents formed by the overlaps through which the internal gases may find their escape while air is effectively excluded.

65 It will be understood that the principle of the invention is independent of the precise plastic used for the wrapper and of the precise oil used, so long as the oil is free flowing at all temperatures to which the package will ordinarily be subjected and the film is oil proof so that the oil will spread by capillarity.

70 What is claimed is:

1. A cheese package comprising a block of cheese enclosed in an oil-proof wrapper which wrapper is impervious to moisture and gases and 75 has a free-flowing oil on its inner face at least

along its two edge portions, the ends of the wrapper being folded over the block of cheese in overlapping relation and the oil-bearing sides of the wrapper being each folded against its respective end of the block of cheese and closing the package, the creases formed by said end folding which open at one end to the atmosphere and at the other end to the interior of the package being filled with said oil.

2. A cheese package as defined in claim 1 in 10 which said creases are folded upon themselves.
